TEXTILE PRINTING FRAME

Ralph E. Bitner, New York, N. Y.

Application May 29, 1940, Serial No. 337,954

8 Claims. (Cl. 101—114)

This invention relates to frames on which textiles may be secured and stretched while being printed by the silk screen process. It also relates to the method and means for attaching the cloth to the frame and means for stretching the cloth after being attached.

The conventional and well known method of printing cloth by the silk screen process employs long tables covered with felt and fabric. A gray cloth or "blotter" is first attached to the table by pinning and then the cloth to be printed is pinned on top of it. The actual printing is accomplished by squeezing dye through a silk screen mounted on a wooden frame. The pattern is formed by blocking out certain portions of the silk by paint or lacquer. During recent years this form of printing cloth has become quite popular because of its flexibility, cheapness and facility of changing patterns.

It is one of the main objects of this invention to eliminate the labor of hand pinning the two cloths to the table.

Another object of this invention is to provide a means for uniformly stretching the cloth to be printed and thereby eliminate the scallops near the selvage.

Another object of the invention is the provision of a mechanism which will permit the printing of the cloth up to the selvage.

Another object of the invention is to provide a printing frame in which no gray cloth is used.

Still another object of the invention is the provision of a printing frame which allows heated air to be circulated under the cloth as well as over it thus drying the dyed cloth in a much shorter time.

Other objects and structural details of the invention will be apparent from the following description when read in connection with the accompanying drawings, wherein:

Fig. 1 is an end view of the printing frame with the end-stretching mechanisms removed.

Fig. 2 is a plan view of one end of the printing frame showing the mechanism for stretching the cloth lengthwise.

Fig. 3 is a detailed plan view of one edge of the printing frame showing an automatic pinning mechanism engaged therewith.

Fig. 4 is a detailed end view of the mechanism shown in Fig. 3 with some parts in section.

Fig. 5 is a partial cross sectional view of the printing frame with a silk screen in printing position.

Fig. 6 is a cross-section taken along line 6—6 of Fig. 1.

Fig. 7 is an enlarged cross sectional view similar to part of Fig. 4 but showing an additional wheel.

Referring now to Fig. 1, the printing frame is supported by a plurality of pipes 10 and 11 which are fastened to the floor by means of threaded flush plates 12. A horizontal pipe 13 joins the vertical pipes 10 and 11 and is secured to them by the usual appropriate fastenings. The pipe 13 also serves as a guide for a roller mechanism which 10 supports one side of the printing frame.

The upper end of each support 10 is provided with a flush plate 14 and on top of each of these plates is secured an angle iron 15 (see Fig. 4) which is used to support and journal a portion of 15 the stretching mechanism. A long flat plate 16 which extends the entire length of the frame is secured to the angle irons 15 and on top of this plate two other angle irons are bolted. One angle iron 17 is provided for use as a printing guide and 20 fulfills the same purpose as the printing guide rails on the present day tables. A small angle iron 18 is bolted to the inside edge of plate 16 and serves as a supporting means for a brass bar 20 in which are mounted a plurality of pins 21. 25

It has been found convenient to use phonograph needles as pins and a spacing of one-quarter of an inch apart is close enough to prevent scallops in the cloth and provide a strong anchorage.

An iron bracket 22 is secured to each angle iron 15 and through a hole in each of these brackets a long shaft 23 is journaled. The shaft 23 extends for the entire length of the machine and since it is not required to transmit large amounts of 35 power, a pipe may be substituted instead of a solid shaft.

A bevel gear 24 is secured to shaft 23 at each bracket and meshing with this gear is another bevel gear 25 mounted at right angles to the first 40 and secured to a horizontal screw 26 which is journaled in the vertical portion of angle iron 15 and extends across the printing frame to a nut 27 attached to the movable rail assembly.

The movable rail is identical in every way to the stationary rail in so far as the upper or pinning portion is concerned. Fig. 6 shows the movable construction in greater detail. The flat plate 16 is bolted to a pair of angle irons 28 which support the nut 27 between them. Four rollers 30 are rotatably mounted between the angle irons as indicated, two above the pipe 13, and two below it. Each roller 30 is provided with a depressed portion on its surface which fits the outside of the 35

pipe 13 and adds considerably to the contact surface. Bolts 31 act as bearings for the rollers.

- It will be obvious from a study of the above construction that a rotation of the screws 26 will 5 cause the entire movable rail to move toward or away from the stationary rail without altering its angular position. Cloth which has been pinned to each row of pins 21 may therefore be stretched by such movement.
- 10 The longitudinal pipe-shaft 23 (Figs. 1 and 2) extends for the entire length of the printing frame and has secured to it, all the gears 24 which may be mounted in the frame.

At one end of the frame a large wheel 33 is 15 secured to shaft 23 and this wheel is coupled by a belt 34 to a much smaller pulley 35 run by an electric motor 36. A suitable electric switch and reversing means (not shown) is employed to turn the mechanism in either direction and impart a 20 transverse motion to the movable rail.

At one or both ends of the frame a stretching device is installed to pull the cloth lengthwise before pinning is started. This mechanism consists of a rotary cylinder 37 (Fig. 2) upon which 25 a plurality of studs 38 is secured. The roller 37 is mounted on a shaft 40 which is journaled in bearings 41 and 42 and a hand wheel 43 is secured to one end of the shaft for manual rotation. A ratchet wheel 44 and a pawl 45 serve as a means 30 to retain the roller assembly in stretched relation while pinning is in progress.

When it is desired to stretch a length of cloth 46 on the printing frame a prepared length of heavy cotton 47 is sewn to each end of the cloth 35 46 for longitudinal stretching. The cotton end pieces 47 have inserted in one edge thereof, a plurality of grommets with a spacing equal to that of the studs 38. The grommets are placed over the studs at each end of the machine and the hand 40 wheels 43 turned until the cloth 46 is stretched to a reasonable degree. The end stretching operation is performed to place the cloth in convenient position for the pinning operation and does not have to be severe. The exertion of one hundred 45 pounds force will generally be sufficient for most jobs.

The cloth is now ready to be impaled on the pins 21. This operation is accomplished by a tool which rolls in the channel formed by the plate 16 50 and the angle irons 17 and 18. It pulls the cloth into alignment, turns it over, and then forces it on the pins 21. In order not to create a bias in the cloth, both edges are pinned at the same 55 time by two operators who walk from one end of the table to the other at approximately the same speed and opposite to each other across the frame.

Fig. 1 shows two of these pinning structures, one in each channel, in the position for pinning operation. Figs. 3 and 4 show the pinner in 60 greater detail. A flat metal base plate 50 serves as a foundation means for the majority of attachments which make up the pinning mechanism. Mounted on the base plate are three rollers 51 which support the plate for longitudinal movement along the frame channel and two side wheels 52 which ride on the angle iron 18 and provide horizontal alignment. A third side wheel 53 is mounted on a lever arm 54, pivoted on the base plate 50 and resiliently stressed by a spring 55. 65 The spring mounting of this wheel keeps the pinner in contact with the angle iron 18 even though there may be irregularities of construction in fabricating the channel.

A flat metal plate 56 is secured to the base plate 70 75 50 by suitable bolts 57 and extends over the angle

iron 18 for a considerable distance. The plate 56 is designed to pass under the cloth during the pinning operation and provides a flat surface to cooperate with a rubber wheel 58 as will be explained later.

Above the plate 56 is another metal plate 60 5 which is secured by the usual bolts and spacers and has a bent-over portion 61 which forces the cloth over into engagement with the pins 21. The cloth obviously passes between plates 56 and 60 10 which plates are spaced properly in accordance with the thickness of the cloth used.

A soft rubber wheel 62 is rotatably mounted 15 between the base plate 50 and a mounting strip 63 which also acts as a brace for the bent-over plate 60. The rubber wheel 62 is mounted in such a manner that the pins 21 pierce its periphery about one-twentieth of an inch. When the selvage of a piece of cloth is guided between the wheel 62 and said pins, the cloth will be forced 20 over the sharp pin points and part way up the shanks.

Mounted alongside of the rubber wheel is a circular brush 64 which pushes the cloth further along the pin shanks and seats it against the 25 brass strip 20. Both wheels 62 and 64 are rotated solely by their contact with the pins and cloth. No other rotative means is necessary.

In order to have just the right amount of selvage bent over and pinned, an adjustable guide 30 must be provided to place the cloth in proper alignment. Such a device is incorporated in the wheel 58 and its control lever 65. The wheel is mounted on an extension bracket 67 attached to a handle 68. As the pinning mechanism is pushed 35 along the channel the cloth slides over plate 56 and under wheel 58 which rotates due to the friction with the cloth surface. As long as the wheel 58 is kept parallel to the line of motion as indicated in Figs. 3 and 4 the cloth will not be moved 40 sideways, but if the wheel is turned at a slight angle by means of the handle 66 the cloth will be forced toward or away from the rail frame. Another handle 70 is shown in the figures since it 45 has been found that the operator produces better results when two hands are used.

Fig. 7 illustrates an alternative method of turning over the cloth and is necessary only when very thin and light grades of cloth are used. The pinning mechanism is the same as that described 50 above except that an extra rubber wheel 71 has been added. This wheel has a concave periphery and is mounted at an angle on a bent bracket 72. The cloth is kept in contact with the edge of plate 56 by this arrangement and is prevented from 55 wrinkling upward as some of the thin fabrics are apt to do. As indicated in Fig. 7, the wheel 71 is turned at a slight angle off the direction of motion. This helps to force the cloth down toward 60 the pins.

After the edges of the cloth have been impaled on both rows of pins the motor 36 is started and the movable rail is moved away from the stationary one until the cloth has been stretched quite tight. The amount of tension will have to be acquired by experience since it varies greatly 65 due to the quality of textiles used.

A standard silk screen 73 (see Fig. 5) is used for the printing operation, the details of which are well known in the textile art and therefore 70 no detailed description is necessary here.

While I have described what I consider to be a highly desirable embodiment of my invention, it is obvious that many changes could be made without departing from the spirit of my invention, 75

and I, therefore, do not limit myself to the exact form herein shown and described, nor to anything less than the whole of my invention as hereinbefore set forth, and as hereinafter claimed.

5. I claim:

1. A pinning mechanism of the class described for securing the selvage of a length of textile fabric to a plurality of pins set in a horizontal bar, said mechanism comprising a slidable base plate arranged for manual movement, an aligning means for positioning the edge of said fabric in correct pinning register, a folding guide plate for turning said fabric over to engage said pins, a resilient roller cooperating with said guide plate 10 for folding said fabric, and a plurality of impaling wheels for successively forcing the selvage of said fabric along the shafts of said pins.

2. A pinning mechanism of the class described for securing the selvage of a length of textile fabric to a plurality of pins set in a horizontal bar, said mechanism comprising a slidable base plate arranged for manual movement, an aligning means for positioning the edge of said fabric in correct pinning register, a folding guide plate 20 for turning said fabric over to engage said pins, and a plurality of impaling wheels for successively forcing the selvage of said fabric along the shafts of said pins.

3. A pinning mechanism of the class described for securing the selvage of a length of textile fabric to a plurality of pins set in a horizontal bar, said mechanism comprising a slidable base plate arranged for manual movement, an aligning means for positioning the edge of said fabric in correct pinning register, a folding guide plate 30 for turning said fabric over to engage said pins and an impaling wheel for forcing the selvage of said fabric over the ends of said pins.

4. A pinning mechanism of the class described for securing the selvage of a length of textile fabric to a plurality of pins set in a horizontal bar, said mechanism comprising a frame arranged for manual movement, an aligning means 40 for positioning the edge of said fabric in correct

pinning register, a folding guide plate for turning said fabric over to engage said pins and an impaling resilient wheel for forcing the selvage of said fabric over the ends of said pins.

5. A pinning mechanism of the class described for securing cloth to a printing frame having a plurality of pins set in the side pieces thereof, said mechanism comprising an aligning means for positioning the edge of said fabric in correct pinning register, said aligning means comprising 10 a wheel for engaging the surface of said fabric, said wheel being horizontally journaled and manually adjustable about a vertical axis; a folding guide plate for turning said fabric over to engage said pins and an impaling resilient wheel 15 for forcing the selvage of said fabric over the ends of said pins.

6. A pinning mechanism of the class described for securing fabric to a printing frame having a plurality of pins set in the side pieces thereof, 20 said mechanism comprising an aligning wheel engaging the surface of said fabric and rotatably mounted on a horizontal axis and manually adjustable about a vertical axis, a folding guide plate for turning said fabric over to engage said 25 pins and an impaling resilient wheel for forcing the selvage of said fabric over the ends of said pins.

7. In a pinning mechanism of the class described for securing the selvage of a fabric to a 30 plurality of pins, an aligning means comprising a movable base plate and an aligning wheel; said base plate arranged to slide under the fabric as the aligning wheel engages the upper surface thereof, and a mounting for said aligning wheel 35 which permits horizontal axial rotation and manual adjustment about a vertical axis.

8. A pinning mechanism of the class described for securing fabric to a frame, said mechanism comprising an aligning wheel engaging the surface of said fabric and rotatably mounted on a 40 horizontal axis and manually adjustable about a vertical axis.

RALPH E. BITNER.
